U.S. Cl. D44—29

FIG. 1.

FIG. 2.

FIG. 3.

FIG. 4.

FIGURE 1 is a perspective view of a handle for hollowware showing my new design, a hollowware pitcher being shown in broken lines for illustrative purposes only;

FIGURE 2 is a side elevational view;

FIGURE 3 is a right end elevational view; and

FIGURE 4 is a top plan view.

The typical hollowware container has been shown in dotted fashion to indicate the relationship between the hollowware and the handle for hollowware.

I claim:

The ornamental design for a handle for hollowware, as shown and described.
